UNITED STATES PATENT OFFICE.

GEORGE ALBERT LYON, OF PHILADELPHIA, PENNSYLVANIA.

AUTOMOBILE BUFFER CONSTRUCTION AND PROCESS OF MAKING THE SAME.

Application filed May 9, 1923. Serial No. 637,670.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Automobile Buffer Constructions and Processes of Making the Same, of which the following is a specification, taken in connection 10 with the accompanying drawing, which forms part of the same.

This application is a partial continuation 15 of my copending application, Serial No. 632,076, filed April 14, 1923, and contains subject matter taken therefrom.

This invention relates to automobile buffers or bumpers in which one or more of the adjustably connected buffer front elements may advantageously be formed of 20 relatively wide thin strip such as spring steel one and three-eighths of an inch thick more or less, which may be bent edgewise to a greater or less extent and then more or less conically bent or otherwise formed as 25 by being diagonally folded to form a transversely extending connector portion and several integrally connected transversely separated strip members which may be oppositely inclined adjacent the connector portion 30 and extend in the same or opposite directions therefrom. Such a buffer element may be advantageously used at the lateral ends of the buffer adjacent the automobile wheels and in such cases the transverse connector portion may have its diagonal folds 35 arranged at substantially right angles to each other so that two transversely separated strips extend horizontally inward from this connector portion to form a double height or 40 double strip buffer element which may extend inward to or past the center of the buffer, if desired, and be adjustably or otherwise joined in overlapping reenforcing position with similar horizontal strip members which 45 are joined by a transverse diagonally folded connector portion at the other side or end of the buffer. Such a buffer front may be supported in any desired way and a spring steel strip supporting attaching member may be 50 arranged to be connected to the two frame ends and have forwardly extending connecting portions secured to these buffer front strip members on each side of the center of the buffer front and within a foot 55 or so of the buffer ends so that these transverse connector portions at the buffer ends

are not subjected to excessive strains which are largely transferred from each of the front strips directly to the connected buffer supporting member which is considerably 60 wider than the vertical separation between the front strips.

In the accompanying drawing showing in a somewhat diagrammatic way various illustrative embodiments of this invention— 65

Fig. 1 is a front view of an illustrative buffer.

Fig. 2 is a bottom view thereof.

Fig. 3 is a detail view showing a partially 70 edge bent buffer strip.

Figs. 4 and 5 show the ends of buffer elements made therefrom.

Fig. 6 shows another partially edge bent 75 strip, and

Figs. 7 and 8 the corresponding ends of 75 buffer elements.

Fig. 9 is a gradually edge bent strip, and

Fig. 10 a buffer element made by folding the same.

In the illustrative buffer shown in Figs. 80 1 and 2 the buffer front may be formed of two elements of relatively wide thin spring steel strip which may be hardened and tempered, if desired. One of these elements may comprise the vertically or transversely 85 separated front strips 1 and 6 connected at the buffer end by an integral connector portion 4 which may have a partial edge bend and two angular or substantially diagonal folds 3, 5 which together space the horizontally 90 extending buffer front strips at the desired distance apart between their adjacent edges 26 and hold them at least throughout the strip ends which form the central part 95 of the buffer in substantial vertical alignment, if desired. The other buffer front element may comprise the vertically separated substantially parallel strips 8, 9 and a similar integral connector portion 4 and these front strips may more or less overlap 100 each other and be adjustably or otherwise connected as by suitable clamping devices 11 which may be arranged adjacent the ends 12, 7 and 9, 10 of these overlapping strips. It 105 is desirable to have the supporting or attaching members securely connected to both the upper and lower strips on each side of the center of the buffer front and preferably adjacent the ends which may, of course, extend into protective position adjacent the 110 automobile wheels. For this purpose the supporting or attaching members may ad-

vantageously be formed with relatively wide inturned connecting portions 13, 19 which may more or less overlap both the vertically displaced buffer front strips and be rigidly connected or clamped thereto by the clamping devices which may comprise the clamping bolts 12. If desired, the entire supporting members may be formed of spring steel strip and may include a transversely extending brace bar portion 16 so as to be conveniently and securely connected to the frame ends of the automobile while suitable curved portions such as 17, 18 and 14, 15 may increase the resilient cushioning action of these supporting members, if desired.

Such buffer front elements may be conveniently made by giving the buffer strips a partial edge bend so that the diverging strip ends are preferably in the same plane. As shown in Fig. 3, the wide flat steel strip may have its connector portion 4 suitably heated and then given an edge bend around forms so that this partial edge bend has a curvature of about 75° which makes the strip ends diverge at about an angle of 105° from each other. A comparatively small degree of curvature may thus be given in the partially edge bent connector portion without unduly straining or distorting the metal even when the radius of curvature is relatively small so that the inner and outer curved edges 21, 22 of this partial edge bend are relatively short radius curves. Such partially edge bent buffer strips 20 may then be folded or more or less conically bent to bring the diverging strip ends into the desired closely spaced substantially parallel position in which at least the strip ends may be in substantial transverse or vertical alignment with each other. This may be accomplished as shown in Fig. 4 by forming diagonal or angular bends 3, 5 in the strip adjacent the partially edge bent connector 4 so that the strip ends 1, 6 extend in the opposite direction from the connector portion or its outer edge 22 as compared to the diverging strip ends of the blank 20. As shown in Fig. 3, these diverging strip ends extend to the left of the connector portion 4 while after these diagonal or angular folds 3, 5 have been formed, the strip ends 1, 6 extend to the right as shown in Fig. 4, without reversing the position of the edge bend 4. In some cases it is unnecessary to form close diagonal or angular folds for this purpose and more gradual or long radius bends or folds 3, 5 may be formed which may in some cases become more or less a somewhat flattened conical bend with advantage. It is also desirable where these angular folds are somewhat gradual bends to have them support the adjacent portions of the front strips in oppositely inclined position as is shown in Figs. 2 and 4 and this causes a slight rearward

inclination of the end of this buffer front element, the strips being oppositely twisted to a slight extent where it is desired to bring them into substantial vertical or transverse alignment. Fig. 5 shows another method of bending or shaping such a partially edge bent strip or blank as is shown in Fig. 3, and in this Fig. 5 construction each of the strips is turned or folded transversely inward toward each other as by the folds 23, 24 so that the strip ends still extend in the same direction from the connector portion 4 or its outer edge 22 as the diverging strip ends did before forming these oblique or inclined folds which may bring the adjacent edges of the front strips 25 into the desired substantially parallel relation to each other. In either of these ways the front strips of these unitary buffer elements may be brought together to within one to four or five inches more or less, as desired, and a strong and reliable integral connector portion may thus be readily bent out of the spring steel strip by hot bending around forms or by die forging operations so as to produce uniformly shaped elements quickly and efficiently.

Fig. 6 shows another form of partially edge bent buffer strip in which the amount of curvature of the connector portion 30 is considerably greater than in Fig. 3. In Fig. 6 the diverging strip ends 28, 29 may form an angle of about 60° with each other so that the partially edge bent connector portion 30 thus has a curvature of about 120° . These buffer strip blanks 27 may be finished by suitable angular or diagonal bending operations as shown in Figs. 7 and 8 so as to secure the desired transverse separation between the front strips and bring them into vertical or transverse alignment to the desired extent. In Fig. 7 two angular folds 33, 34 are formed in the strip on each side of the edge bent connector portion 30 so that these connected strip ends 28, 29 may be securely supported with their edges 35 at the desired distance apart. This forms a good design of buffer front element for such spacing as two or three inches between the edges of the parallel front strips. Fig. 8 has a lighter and more tapered contour in the end of the buffer element because of the more nearly parallel position of the angular bends or folds 36, 38 which are formed on each side of the partially edge bent connector portion 30. By forming these folds relatively near the central part of this edge bend part of the outer curved edge 31 may be utilized as the inner adjacent edge 39 of these inwardly folded strips which gives a decidedly distinctive appearance to this unitary buffer element. Of course the radii of curvature of the outer and inner edges 31, 32 of these partially edge bent connector portions 30 may be given any suitable value

which is proper, considering the thickness and width of the strip used, and for some purposes it is somewhat better to have a rather sharp curvature with such a construction as is shown in Fig. 8, although it is not of course necessary in all cases.

It is sometimes advantageous to form buffer elements or strips of wide thin spring steel with a complete gradual or long radius edge bend as shown in Fig. 9, so as to bring the strip ends 41, 45 into parallel, although widely separated position with respect to each other. With relatively thin wide strip and edge bent connector portion 42 may be bent into semi-circular form without undesirable weakening or distortion when the radii of curvature are six to eight inches more or less, depending of course on the heats and bending methods employed. Such a blank 40 may have its strip ends bent or folded inward toward each other as shown in Fig. 10 so as to bring the inner portions of these front strips 41, 45 into parallel transversely aligned position, if desired, with their inner edges three to five inches apart. In this way the inwardly curved or extending portions 47, 50 of the strip adjacent the connector portion 42 are part of the edge bend and serve to carry the front strips inward into closer spaced parallel position as indicated. In this way only a part of the complete gradual edge bend may be utilized between the folds 46, 48 which may be more or less parallel in this instance, this depending of course on the degree of separation desired between the front strips and the amount and sharpness of the edge bend originally given to the blank.

This invention has been described in connection with a number of illustrative forms, proportions, parts, arrangements, materials, methods of connection and use, to the details of which disclosure the invention is not of course to be limited, since what is claimed as new and what is desired to be secured by Letters Patent is set forth in the appended claims:

1. The automobile buffer comprising two adjustably connected elements formed of wide thin steel strip and each comprising vertically spaced horizontally extending portions and an integral connector portion of the strip partially edge bent and having an angular diagonal fold on each side of the center of the edge bend at the end of the element holding the horizontally extending vertically spaced portions of the strips in substantial vertical alignment and with their adjacent edges about two to five inches apart and steel strip supporting attaching members adapted to be secured to the automobile frame and having laterally extending in-turned ends rigidly secured to both vertically separated portions of each of said elements adjacent the ends of said buffer front.

2. The automobile buffer comprising two adjustably connected elements formed of wide thin steel strip and each comprising vertically spaced horizontally extending portions and an integral connector portion of the strip partially edge bent and having an angular fold on each side of the center of the edge bend at the end of the element holding the horizontally extending vertically spaced portions of the strips with their adjacent edges about two to five inches apart and attaching members adapted to be secured to the automobile frame and having laterally extending in-turned ends rigidly secured to said elements adjacent the ends of said buffer front.

3. The automobile buffer comprising two connected elements formed of wide thin steel strip and each comprising vertically spaced horizontally extending portions and an integral connector portion of the strip partially edge bent and having an angular fold on each side of the center of the edge bend at the end of the element holding the horizontally extending vertically spaced portions of the strips in closely spaced substantial vertical alignment adjacent the center of the buffer front, and steel strip attaching members adapted to be secured to the automobile frame and having laterally extending portions rigidly secured to both vertically separated portions of said elements adjacent the ends of said buffer front.

4. The automobile buffer comprising two connected elements formed of wide thin steel strip and each comprising vertically spaced portions and an integral connector portion of the strip partially edge bent and having an angular fold on each side of the center of the edge bend at the end of the element holding the vertically spaced portions of the strips in closely spaced substantial vertical alignment adjacent the center of the buffer front, and attaching members adapted to be secured to the automobile frame and having portions rigidly secured to both vertically separated portions of said elements.

5. The automobile buffer comprising a pair of adjustably connected elements formed of wide thin steel strip and each comprising vertically spaced portions and an integral connector portion of the strip partially edge bent and having an angular fold on each side of the center of the edge bend at the end of the element holding the adjacent vertically spaced portions with their adjacent edges about two to five inches apart and arranged in oppositely inclined angular position, said vertically spaced portions being oppositely twisted adjacent said connector portion and attaching members adapted to be secured to the automobile frame and having laterally extending in-turned end portions rigidly secured to both vertically separated portions of said elements.

6. The automobile buffer comprising a pair of adjustably connected elements formed of wide thin steel strip and each comprising vertically spaced portions and an integral connector portion of the strip partially edge bent and having an angular fold on each side of the center of the edge bend at the end of the element holding the adjacent vertically spaced portions in oppositely inclined angular position, said vertically spaced portions being oppositely twisted adjacent said connector portion and attaching members adapted to be secured to the automobile frame and having portions rigidly secured to both vertically separated portions of said elements.

7. The automobile buffer comprising a pair of adjustably connected elements formed of wide thin steel strip and each comprising vertically spaced portions and an integral connector portion of the strip partially edge bent and having an angular bend on each side of the center of the edge bend at the end of the element holding the adjacent vertically spaced portions in oppositely inclined angular position, said vertically spaced portions being oppositely twisted adjacent said connector portion, and attaching members adapted to be secured to the automobile frame and rigidly secured to both vertically separated portions of said elements.

8. The automobile buffer comprising a pair of adjustably connected elements formed of wide thin steel strip and each comprising vertically spaced portions and an integral connector portion of the strip edge bent and having an angular bend on each side of the center of the edge bend at the end of the element holding the adjacent vertically spaced portions in oppositely inclined angular position, and attaching members adapted to be secured to the automobile frame and rigidly secured to said elements.

9. The automobile buffer comprising connected elements formed of wide thin tempered spring steel strip and each comprising transversely spaced horizontally extending portions and comprising at the end of the element an integral connector portion of the strip partially edge bent and having an angular fold on each side of the center of the edge bend to hold the transversely spaced portions in substantial transverse alignment with their adjacent edges about one to four inches apart, and attaching members adapted to be secured to the automobile frame and having laterally extending connecting portions secured to both transversely separated portions of said element.

10. The automobile buffer comprising connected elements formed of wide thin tempered spring steel strip and each comprising

transversely spaced portions and comprising at the end of the element an integral connector portion of the strip partially edge bent and having an angular fold on each side of the center of the edge bend to hold the transversely spaced portions in substantial transverse alignment and attaching members adapted to be secured to the automobile frame and having connecting portions secured to both transversely separated portions of said element.

11. The automobile buffer front comprising two laterally adjustably connected elements formed of wide thin steel strip and each comprising vertically spaced horizontally extending portions and an integral connector portion of the strip partially edge bent and having an angular fold on each side of the center of the edge bend at the end of the element holding the horizontally extending vertically spaced portions of the strips in closely spaced substantial vertical alignment adjacent the center of the buffer front with their adjacent edges about two to five inches apart.

12. The automobile buffer front comprising two connected elements formed of wide thin steel strip and each comprising vertically spaced portions and an integral connector portion of the strip partially edge bent and having an angular fold on each side of the center of the edge bend at the end of the element holding the vertically spaced portions of the strips in closely spaced substantial vertical alignment adjacent the center of the buffer front.

13. The automobile buffer front element formed of wide thin tempered spring steel strip and comprising transversely spaced portions and comprising at the end of the element an integral connector portion of the strip partially edge bent and having an angular fold on each side of the center of the edge bend to hold the transversely spaced portions with their adjacent edges about one to four inches apart, the rear face of the said connector portion and the front faces of the adjacent transversely displaced front portions being polished and nickel plated in contrast to other parts of the element.

14. The automobile buffer front element formed of wide thin steel strip and comprising transversely spaced portions and comprising at the end of the element an integral connector portion of the strip edge bent and having an angular fold on each side of the center of the edge bend to hold the transversely spaced portions.

15. The automobile buffer element formed of wide thin tempered spring steel strip and comprising transversely spaced portions and comprising at the end of the element an integral connector portion of the strip partially edge bent and having a diagonal fold on each side of the center of the edge

- bend to hold the transversely spaced strip ends in substantial transverse alignment with their adjacent edges about two to four inches apart, the rear face of the said connector portion and the front faces of the adjacent transversely displaced front portions being polished and prominently finished in contrast to other parts of the element.
10. 16. The automobile buffer front element formed of wide thin steel strip and comprising transversely spaced portions and an integral connector portion at the end of the element and comprising a partial edge bent portion and angularly folded portions on each side thereof holding the adjacent transversely displaced portions in closely spaced oppositely inclined positions with the strip ends in substantially aligned position, the rear face of the said connector portion and the front faces of the adjacent transversely displaced portions being polished and prominently finished in contrast to other parts of the element.
15. 17. The automobile buffer front element formed of wide thin steel strip and comprising transversely spaced portions and an integral connector portion at the end of the element and comprising an edge bent portion and folded portions on each side thereof holding the adjacent transversely displaced end portions in closely spaced oppositely inclined positions with the strip ends in aligned position.
20. 18. The automobile buffer front element formed of wide thin steel strip and comprising vertically spaced horizontally extending portions and an integral connector portion at the end of the element and comprising a partial edge bent portion and angularly folded portions on each side thereof holding the connected vertically displaced portions in closely spaced substantially vertically aligned position.
25. 19. The automobile buffer front element formed of wide thin steel strip and comprising vertically spaced portions and an integral connector portion at the end of the element and comprising a partially edge bent portion and angularly folded portions on each side thereof holding the connected vertically displaced portions in closely spaced position.
30. 20. The automobile buffer element formed of wide thin steel strip and comprising vertically spaced portions and an integral connector portion at the end of the element and comprising a partially edge bent portion and angularly bent portions on each side thereof holding the connected vertically displaced portions in closely spaced position.
35. 21. The process of forming an automobile buffer front element of wide thin spring steel strip which comprises heating an intermediate connector portion of the strip and forming therein a partial edge bend from which the strip ends diverge in substantially the same plane, forming an angular fold in said strip on each side of the center of the edge bend to bring the end portions of the strip into substantially parallel transversely spaced position in substantial alignment with each other, and hardening and tempering the element.
40. 22. The process of forming an automobile buffer front element of wide thin spring steel strip which comprises heating an intermediate connector portion of the strip and forming therein a partial edge bend from which the strip ends diverge, forming an angular fold in said strip on each side of the center of the edge bend to bring the end portions of the strip into substantially parallel transversely spaced position and hardening and tempering the element.
45. 23. The process of forming an automobile buffer front element of wide thin steel strip which comprises forming in an intermediate connector portion of the strip a partial edge bend from which the strip ends diverge in substantially the same plane, and forming an angular fold in said strip on each side of the center of the edge bend to bring the end portions of the strip into substantially parallel transversely spaced position and extending in the same direction from the outside of the edge bend as the originally diverging strip ends.
50. 24. The process of forming an automobile buffer element of wide thin steel strip which comprises forming in an intermediate connector portion of the strip a partial edge bend from which the strip ends diverge, and forming an angular fold in said strip on each side of the center of the edge bend to bring the end portions of the strip into transversely spaced position and extending in the same direction from the outside of the edge bend as the originally diverging strip ends.
55. 25. The process of forming an automobile buffer element of wide thin spring steel strip which comprises heating the strip and forming in an intermediate connector portion thereof a partial edge bend from which the strip ends diverge in substantially the same plane, forming an angular bend in said strip on each side of the center of the edge bend to bring the end portions of the strip into transversely spaced position in substantial alignment with each other, and hardening and tempering the element.

GEORGE ALBERT LYON.
